(57) CLAIM

I claim the ornamental design for a bra, as shown and described.

DESCRIPTION

FIG. 1 is a right, rear perspective view of a bra, showing my new design;

FIG. 2 is a rear view thereof;

FIG. 3 is a left, rear perspective view thereof;

FIG. 4 is a left side view thereof;

FIG. 5 is a right side view thereof; and,

FIG. 6 is an enlarged view of the selected region of FIG. 1. The dot-dash broken line rectangles depict the limits of the enlarged view and form no part of the claimed design. The regular broken lines depict features of the bra that form no part of the claimed design.
